UNITED STATES PATENT OFFICE

RICHARD KITSON, OF LOWELL, MASSACHUSETTS.

IMPROVEMENT IN DUST-ROOMS CONNECTED WITH MACHINES FOR PICKING COTTON, &c.

Specification forming part of Letters Patent No. **36,219**, dated August 19, 1862.

To all whom it may concern:

Be it known that I, RICHARD KITSON, of Lowell, in the county of Middlesex and State of Massachusetts, have invented a new and useful Improvement in Dust-Rooms Connected with Machines for Picking and Opening Cotton and other Fibrous Materials; and I do hereby declare that the following is a full, clear, and exact description of the same, reference being had to the accompanying drawings, forming part of this specification, in which--

Figures 1 and 2 are vertical sections at right angles to each other of a dust room with my invention applied.

Similar letters of reference indicate corresponding parts in the two figures.

All cotton openers and pickers and machines for picking and burring wool of modern construction have their own suction-fans independent of each other, and it is customary to connect with several of these fans dust-pipes which all terminate and discharge into a dust-room; but there is one difficulty connected with this arrangement which I wish to obviate, which is as follows: Whenever it is necessary to stop one of the machines, the pressure of the air in the dust-room, produced by the fans of the machine, which continue in operation, being greater than the pressure of the atmosphere in the picker-room, forces the air and dust back through the dust-pipe of the machine that is stopped into the picker-room.

The object of my invention is to obviate this difficulty; and to this end it consists in fitting the dust-pipes of the pickers with valves which close automatically when their respective machines are stopped.

To enable others skilled in the art to make and use my invention, I will proceed to describe its construction and operation.

A is the dust-room, fitted below its roof with a screen, B, for the retention of any fiber that may be carried into it by the draft in the dust-pipes, and having openings *a a* in the roof for the escape of the dust.

C C C are three dust-pipes belonging to three pickers, and D D D are the valves fitted to the mouths of the dust pipes. These valves are of the kind known as "flap-valves," and are suspended from pins *b b* in such manner as to close the mouths of the pipes by gravitation when the pressure of air in the pipes is no greater than that in the dust-room, but to be opened easily by the pressure in the pipes when such pressure is greater than that in the dust-room, and by that means to provide for the discharge of the dust into said room when the machine is running and its fan-in operation. By thus closing when the pressure in the pipe is less than that in the dust-room the said valves effectually prevent any back-pressure in the pipes and the return of dust through them into the picker-room when their respective machines are stopped.

What I claim as my invention, and desire to secure by Letters Patent, is--

Furnishing the dust-pipes of the pickers or openers with valves D D D, closing automatically, substantially as herein specified.

RICHARD KITSON.
